TIME CALCULATOR

Filed April 12, 1922

Patented June 12, 1923.

UNITED STATES PATENT OFFICE.

RICHARD N. GARDNER, OF SAN FRANCISCO, CALIFORNIA.

TIME CALCULATOR.

Application filed April 12, 1922. Serial No. 551,799.

To all whom it may concern:

Be it known that I, RICHARD N. GARDNER, a citizen of the United States, residing at the city and county of San Francisco and the State of California, have invented certain new and useful Improvements in Time Calculators, of which the following is a specification.

My invention relates to the class of slide rule calculators, and is particularly adapted for calculating elapsed time.

The object of my invention is to provide a device for calculating the elapsed time of workmen, between going on and going off duty, and further to calculate the over-time, or time spent on duty over a certain specified length of time, and for which a greater rate of wage is allowed.

My device is particularly well adapted for use in calculating the time of railway workmen, for the reason that such men, particularly those in train and yard service, go on and off duty at odd times, and work for various and unequal lengths of time. In such work, my calculator is of use not only to determine the elapsed time and over-time spent by the workman on duty, for the purpose of calculating his pay therefor, but also to determine the hour at which he shall be relieved from or called for duty after he has worked for the maximum permitted shift or has been off duty for the required length of time. Such calculations, if made by pencil and paper are troublesome and lengthy; especially in the case of railway men whose hours are irregular, and are further subject to error. By the use of my device, however, they may be made instantly and with great accuracy.

An additional feature of my invention is that the total elapsed time and the over-time are taken from the scales as separate figures, although both are determined by one setting of the device, and appear in adjacent positions. This is also of advantage in railway work, for the reason that elapsed, or "straight" time and over-time, and the amounts paid therefor, are always kept separate in the compilation of statistics.

It is to be understood, however, that my device is not limited to use in railway work, but may be used for determining the time of employees in any industry or shop, or for calculating the elapsed time between any two known limits for any purpose whatsoever. Moreover, although my invention is

herein described and illustrated in its preferred form, it is to be understood that changes may be made in the form and construction of the device within the scope of the claims hereto appended.

My invention will now be fully described with reference to the accompanying drawings, wherein—

Fig. 1 is a plan view, broken, of my time-calculator, the slides being shown in their fully retracted positions.

Fig. 2 is a similar view showing the elapsed time slide partly extended.

Fig. 3 is a similar view showing both slides partly extended.

Fig. 4 is a transverse section, taken on the line 4—4 of Fig. 3, and viewed in the direction of the arrows.

In the drawings, the reference numeral 1 designates the body of my calculator, and is formed after the manner of the well-known slide-rule, having in its face a groove 2 extending for its full length. Said groove has undercut sides, forming a guide for a slide 3, also extending the full length of the body 1, and capable of sliding in either direction therein. The slide 3 is also provided with an undercut groove 4, extending for a portion of its length, and in which is mounted a second slide 5. This second slide thus extends from a point somewhat back from the left hand end of the first slide 3 to the right hand end thereof, and is capable of being moved toward the right from its normal position shown in Fig. 1.

The body 1 is provided, along its upper portion adjacent to the upper edge of the slide 3, with a scale 6 having equally spaced graduations representing the hours and minutes of the clock, the smallest graduations preferably representing five minute intervals. This scale extends the entire length of the body 1, and, in the example shown in the drawings, begins with the 12th hour at the left hand end, (which may be taken either as noon or midnight) and runs consecutively to the second 9th hour following, at the right hand end, representing a total time of 21 hours. The length of the body 1, and of the clock scale 6, is immaterial. They may be longer or shorter, depending upon the class of service for which the device is designed. Similarly, the unit graduation of said scale 6 may be given any desired value, depending upon the use for which the device is made. The essential

features of the scale 6, however, are that it must represent time as expressed by the clock, and that its graduations must be equally spaced throughout its length. Said 5 scale 6 is suitably marked with the proper figures, preferably as shown in the drawings, to enable rapid and accurate reading. The larger, or full-length slide 3 is also 10 provided with a scale 7, whose graduating lines extend from the upper edge of said slide 3 to the upper edge of the smaller slide 5, and correspond, in spacing and unit value, with the unit graduations of the clock-scale 6 throughout its entire length. In 15 the example shown in the drawings, the unit value of the slide scale 7 is therefore 5 minutes, corresponding to the 5 minute interval between the unit graduations of the clock-scale 6. The graduations of the slide 20 scale 7 are designated by figures placed immediately to the left of each graduating line in the space between it and the preceding line. Said figures are placed one below the other, for convenience in lettering and reading, and should be read from the top down, the upper one or two figures representing hours and the lower two representing min- 25

utes. Thus the figures 0 in the second 30 2 5 5

space from the right-hand end of the scale 7, in Fig. 1, should be read "20 hours and 55 minutes". Said scale 7, as will be seen, 35 begins with 0 at the left-hand end of the slide 3, and progresses continuously by 5-minute intervals to 21 hours at the right-hand end. In actual practice each gradu- 40 ating line of the scale 7 will be numbered, but, for the sake of clearness the greater part of such numbers have been omitted from the drawings.

The scale 7 may be termed the elapsed-time scale, and its function is to calculate 45 the number of hours and minutes elapsing between two known points of time on the fixed clock-scale 6. For example, if the problem is to determine the time elapsing between 1.55 a. m. and 6.20 p. m., the zero 50 mark on the elapsed-time scale 7 is placed at the mark indicating 1.55 on the clock-scale 6, as shown in Fig. 2. Then the desired result, 16 hours and 25 minutes, will be found on the elapsed-time scale 7 be- 55 low the second 6.20 mark on the clock-scale 6.

For convenience, I prefer to provide a short additional clock-scale 6', similar to the scale 6, on the lower portion of the 60 body 1 adjacent to the lower edge of the slide 3, said scale 6' beginning with 5 o'clock at the left-hand end of said body 1 and running consecutively to 12 o'clock, or 7 hours. A zero mark 7' is placed on the 65 lower portion of the slide 3 for use with

said scale 6', said zero mark 7' standing at 12 on said scale 6' when the zero mark of the main elapsed-time scale 7 stands at 12 on the main clock-scale 6. Thus for initial settings between 5 and 12 o'clock, the 70 slide 3 can be moved to the left and set by means of the zero mark 7' and the scale 6'. This gives a greater range of calculation, and avoids having to move the slide 3 to the right beyond 5 o'clock on the clock- 75 scale 6.

The inner and shorter slide 5 is provided with a scale 8, which may be termed the over-time scale, said scale having graduations throughout its length similar to and 80 corresponding with the graduations of the elapsed-time scale 7. The figures designating the values of the graduations of said over-time scale 8 are arranged similarly to those of the scale 7, that is, the figures are 85 placed to the left of the line to which they refer, and are arranged one below the other, the upper figures representing hours and the lower ones minutes, and they progress consecutively from left to right. As in 90 the case of the elapsed-time scale 7 previously described, each graduation of the scale 8 should be marked with figures representing its value, but for the sake of clearness the greater portion of these figures have been 95 omitted from the drawings. The unit-value of the over-time scale 8, however, de- 100 pends on the wage rate paid for over-time work in the particular industry for which the scale is made. The ratio between the unit value of the over-time scale 8 and that of the elapsed-time scale 7 is equal to the ration between the increase in the wage rate paid for over-time work and the basic or straight-time wage rate. Thus in the ex- 105 ample shown in the drawings, which is de- 110 signed for use in calculating the time of men receiving "time and one-half" or a 50% increase for over-time work, the unit value of the over-time scale 8 is one-half 115 that of the elapsed-time scale 7, or 2½ minutes. If the over-time rate were "double- 120 time", or a 100% increase over the straight time rate, the unit value of the over-time scale 8 would be the same as that of the elapsed-time scale 7. If the calculator is to be used in a factory in which different 125 classes of workmen receive different over- 130 time rates, a different slide 5 must be provided for each such rate, it being necessary merely to substitute one slide for another when changing from the calculations of one rate to those of another.

The effect of this valuation of the over-time scale 8 is to adjust the actual over-time 125 to an apparent figure (expressed in hours and minutes) which can be either added di- 130 rectly to the straight, or elapsed time, or calculated, for determining the wage to be paid, at the straight-time rate. This re-

sults in a considerable saving of time and trouble in figuring pay rolls, and decreases the chance of error. For example, if a man works from 1.55 a. m. to 6.20 p. m. his 5 elapsed time is 16 hours and 25 minutes, as shown in Fig. 2 and explained above. Reading down on the overtime scale 8 immediately below 16.25 on the elapsed-time scale 7, the time-keeper finds the figures 4 hours 10 12 $\frac{1}{2}$ minutes. He then merely adds this amount to the elapsed time, giving 20 hours 37 $\frac{1}{2}$ minutes, and multiplies this sum by the straight-time rate to determine the total wage due the workman. There is necessary, 15 therefore, only one addition and one multiplication, whereas if the overtime were kept at its actual time value of 8 hours and 25 minutes, the elapsed time (16 hours and 25 minutes) would have to be multiplied by 20 the straight-time rate, and the overtime (8 hours and 25 minutes) by the excess overtime rate (or 50% of the straight-time rate), and the two results added together to give 25 the total wage, thus involving two multiplications, at different rates, and one addition. This elimination of one step in the calculation results in a considerable saving in time, as well as increased accuracy, where large 30 numbers of workmen are involved, and more especially when pay rolls are figured monthly or at similar intervals.

It has been assumed in the above that the overtime is to be paid only after the expiration of eight hours work, and in such cases 35 the zero point on the overtime scale 8 falls beneath the 8 hour point on the elapsed-time scale 7, as shown in Figs. 1 and 2. If, however, overtime is to be paid after any greater length of time, the overtime slide 5 40 is moved to the right until the zero point of the overtime scale 8 falls under the point on the elapsed-time scale 7 at which such overtime begins. Thus, for example, if overtime is to be paid after 9 hours work, the 45 slide 5 is moved to the position shown in Fig. 3, so that the zero point of the overtime scale falls under the 9 hour line of the elapsed-time scale 7. Assuming the elapsed-time to be 16 hours and 25 minutes, as before, the apparent overtime value is now 3 50 hours and 42 $\frac{1}{2}$ minutes, giving an apparent total of 20 hours and 7 $\frac{1}{2}$ minutes to be paid for at the straight-time rate.

In the typical form of my invention here-with illustrated the left-hand limit of movement of the over-time slide 5 is fixed at the 8 hour line on the elapsed-time scale 7, for the reason that overtime is usually figured after eight hours, and it is convenient to push said slide 5 to its stop when figuring the greatest number of calculations. However, the groove 4 of the over-time slide 5 may be of such a length that said slide will stop at any other desired point, depending upon the working conditions in the industry for which the device is intended.

It should be noted that my calculator does not combine the elapsed time and the overtime in one result, but gives them separately, the overtime being expressed in terms of the straight-time rate. This is of particular advantage in the compilation of statistics, and especially in railway work, for the reason that elapsed time and overtime are always kept separate in such statistics.

Another example of the uses of my calculator is in determining the hour at which a man may go on or off duty, after fixed periods of rest or work. For instance, a certain train-man has been on duty continuously since 1.55 a. m. Regulations provide that he must be relieved after 16 hours of duty. Setting the zero point of the scale 7 at 1.55 on the clock-scale 6, as in Fig. 2, the hour at which this man must be relieved, viz. 5.55 p. m. is found on said scale 6 above the 16 hour line on the scale 7.

I claim:—

A slide rule calculator comprising a body member having a fixed scale; a movable slide 90 having a scale for indicating the arithmetical difference between any two given points on the fixed scale; and a second movable slide, said second slide having a scale for indicating in terms of a predetermined coefficient 95 the arithmetical difference between any two given points on the scale of the first slide.

In testimony whereof I have signed my name to this specification.

RICHARD N. GARDNER.
